UNITED STATES PATENT OFFICE.

RICHARD J. PLAATJE, OF NEW YORK, N. Y.

THREAD-GUIDE FOR SEWING-MACHINES.

1,034,832.

Specification of Letters Patent.

Patented Aug. 6, 1912.

Application filed September 1, 1911. Serial No. 647,287.

To all whom it may concern:

Be it known that I, RICHARD J. PLAATJE, of New York, Kings county, New York, have invented a new and useful Improvement 5 in Thread-Guides for Sewing-Machines, of which the following is a full, clear, and exact description.

My invention relates to improvements in sewing machine attachments.

With the ordinary sewing machine a good deal of difficulty is experienced from the fact that the thread, as it is pulled along by more or less intermittent movement, will sometimes jump over the end of the spool 15 and get entangled on the spindle. When this happens, the thread is often broken, or if not broken, it is knotted or if neither occurs, it gets entangled so that the operator has to stop and fix it. Moreover, in such 20 cases, the thread will sometimes pull hard enough on the point of the needle to deflect it slightly and it will strike on some part of the machine and break the needle point.

The object of my invention is to produce 25 a very simple and inexpensive attachment, which can be easily attached to or taken from the arm of any sewing machine and which will guide the thread so as to prevent any of the above-mentioned difficulties. 30 Further, I arrange the device so that it acts in a measure, as a tension device and improves the tension on the thread.

Reference is to be had to the accompanying drawings forming a part of this specification, in which similar reference characters refer to similar parts throughout the several views.

Figure 1 is a perspective view showing, in a general way, a common form of sewing 40 machine with my attachment applied thereto. Fig. 2 is a plan view on an enlarged scale, of the attachment. Fig. 3 is a side elevation of the attachment and Fig. 4 is a front view thereof.

The spindle 10 is common to all sewing machines and is generally arranged on the top of the arm or near its base. This spindle is adapted to receive one of the holes 10^a in the base plate 12 of the attachment, and 45 it also receives the spool 11 which sits on the spindle as usual and rests on the plate 12. There are two of these holes 10^a shown, the spindle 10 extending through one of them, but a greater or less number can be 50 provided and the object is to bring the spool nearer to or farther away from the guide 55

hereinafter referred to, according as the spool is relatively large or small. If a small spool is used, it is naturally placed nearer the guide and so the hole 10^a nearest the 60 guide, is slipped on over the spindle 10.

The plate 12 is provided with a vertical member 13 and near the junction the plate 12 is bent downward, as shown at 14, so that this member 14 will set firmly on the arm of 65 the sewing machine. I make this bend because sewing machine arms are of different shapes and this enables the device to be adapted to any usual shape of arm. The member 13 is provided with a slot 15 70 through which the thread 16 runs, and a guide rod 17 is arranged vertically behind the member 13 and between it and the spindle 10 and spool 11. This rod 17 can be in the form of a simple wire and can be at- 75 tached in any convenient way. I have shown a convenient arrangement in which the top of the wire or rod is bent forward, as shown at 18, and attached to the top of the member 13 while the bottom extends 80 through the plate 12 and is bent to form a keeper 19 in which is pivoted the clamp 20. This clamp, as shown, is a U shaped spring adapted to straddle the arm of the sewing machine and clamp the device in place but 85 obviously, a great many kinds of clamps might be used without departing from the principle of the invention. The object in having it pivoted, as shown, is to enable it to fold up flatwise against the plate 12 for 90 convenience in shipping and handling when the device is not in position on the sewing machine.

When the device is to be used, the plate 12 is placed over the spindle 10 so as to lie flat- 95 wise on the arm of the machine and if a small spool is to be used, the spindle is in- serted in the front hole of the plate 12 and if a larger spool is to be used, it is inserted farther back and, as previously stated, as 100 many holes can be provided as may be nec- essary. The thread is then run to one side of the guide rod 17 through the slot 15 of the member 13, and is threaded through the machine in the ordinary manner. It will be 105 noticed by reference to Fig. 2 that this ar- rangement causes the thread to draw at an angle across the rod 17 so that the latter serves as a tension device and the slot 15 ef- fectually prevents the thread from jumping 110 over either end of the spool. It will be fur- ther observed that the device can be in-

stantly applied to or removed from the machine.

It will, of course, be understood that the device can be made in very many different 5 designs and that the shape of the parts is not very essential, the main thing being to provide a suitable base which can be applied to the spindle 10 and in which the 10 guide slot 15 and guide rod 17 will have the right relation to the spool. Also that a suitable clamping device be used for attaching the guide to the machine.

I claim:

1. A thread guide for sewing machines 15 comprising a base portion adapted to ride on the arm of a sewing machine and having means for connecting with the spool spindle, a vertical perforated member leading from said base, a guide rod extending downward 20 from the top of the perforated member to the base and behind the perforation in said vertical member, and a fastening device to secure the base to the arm of the sewing machine in advance of the spool spindle.

2. A thread guide for sewing machines, 25 comprising a base having an adjustable connection with the spool spindle of a sewing machine and adapted to ride on the sewing machine arm, a vertical member rising from the base and having a thread hole there- 30 through, a guide rod behind the vertical member, and a spring clamp attached to the base and adapted to fasten it to the sewing machine arm.

3. A thread guide for sewing machines 35 comprising a base portion adapted to ride on the arm of a sewing machine, a vertical perforated member leading from said base, a guide rod vertically arranged behind the perforations in said vertical member, and 40 means to secure the base to the arm of the sewing machine a definite distance in advance of the spool spindle.

RICHARD J. PLAATJE.
